SHEET-PILER

Dario Buccicone, Gary, Ind., assignor to Buccicone Engineering Co., Inc., Gary, Ind., a corporation of Indiana

Filed Oct. 31, 1958, Ser. No. 770,969
18 Claims. (Cl. 271—68)

This invention relates to apparatus for piling metal sheets as they are received from a high speed processing line and is more particularly concerned with improvements in edge aligning devices for such apparatus.

In the handling of metal sheets where the sheets are delivered from a high speed processing line apparatus has heretofore been provided for accumulating the sheets in a pile on a suitable support such as an elevator beneath an overhead delivery conveyor which apparatus includes mechanism for stopping the forward movement of the sheet and allowing the same to drop on the pile beneath the conveyor and mechanism for guiding the side edges of the sheets as they settle onto the pile. In order to adapt the piling apparatus to the handling of sheets of different size, it is desirable to mount the end stop mechanism and the side guide mechanisms so that they may be adjustably positioned to accommodate sheets of different size. Previous arrangements for providing adjustability for the end stop and side guide mechanisms have not been entirely satisfactory principally because of the time required to make the adjustments and the liability to damage through careless operation. It is an object, therefore, of the present invention to provide improved mechanism for adjustably mounting the end stop and side guides of a sheet piling apparatus so that the apparatus may be adjusted quickly to accommodate sheets of different size while it is in operation and the possibility of damage which may be caused by careless operation of the machine is minimized.

It is a more specific object of the invention to provide an apparatus for handling metal sheets which comprises an overhead conveyor for advancing successive metal sheets to a point for delivery onto a pile beneath the conveyor and end stop and side guide mechanisms which are mounted on slideable carriages connected to driven adjusting screws which are adapted to be rotated without stopping the conveyor for rapid and accurate positioning of the end stop and side guide mechanisms.

It is a further object of the invention to provide in a piler for handling metal sheets an overhead magnetic conveyor to which the sheets are delivered for deposit on a pile and a pair of side guide devices having carriages at their opposite ends which are supported for transverse movement on end cross rails and equalizing mechanisms for holding the side guides in parallel relation while the distance between the guide faces thereof is adjusted.

It is another object of the invention to provide in a sheet piler having an overhead magnetic conveyor on which sheets are advanced for deposit in a pile on a support beneath the same, a pair of side guides having the ends thereof supported in sliding relation on longitudinally spaced, transversely extending guide rails and a single adjusting screw connected at its opposite ends to corresponding ends of the side guides for adjusting the distance between the guide faces of the side guides together with mechanism for holding the side guides in parallel relation as they are adjusted by operation of the adjusting screw.

It is still a further object of the invention to provide a sheet piler having an overhead magnetic conveyor and side guide devices beneath the same which are mounted for adjustment toward and from each other wherein the side guides are separably connected at opposite ends to

2

carriages which are mounted on transversely extending guide rails so as to permit substantially free vertical movement of the side guides when a lifting force is applied thereto and thereby prevent accidental damage to the side guides or their mounting means.

It is another object of the invention to provide a sheet handling apparatus comprising an upright supporting frame, an overhead magnetic conveyor arranged on the frame for advancing successive metal sheets to a point for deposit on a pile beneath the same, side guide members carried in parallel relation on the supporting frame and having oppositely disposed, vertically extending sheet edge guiding faces, transversely extending, horizontally disposed, longitudinally spaced racks arranged on the frame, each of the side guide members having rotatably mounted thereon a longitudinally extending shaft which is provided at opposite ends with pinions positioned for operating engagement with said racks and a single adjusting screw journaled in transversely extending relation at one end of the supporting frame which adjusting screw has a drive means and carries a pair of traveling nuts adapted to be moved toward and from each other upon rotation of the screw, and the side guide members each having a bracket at the end adjacent the adjusting screw 25 with means forming a separable connection between the nuts and the brackets whereby the distance between the side guide members is uniformly adjusted upon rotation of the screw.

It is another object of the invention to provide in a sheet piler having an upright support frame and an overhead belt type magnetic conveyor, an end stop mechanism with an adjustable mounting therefor, wherein the mounting comprises a carriage on which the end stop is supported, a track formation extending longitudinally of the piler on which the carriage is adapted to move, a driven adjusting screw mounted in parallel relation adjacent the track formation, and having a traveling nut thereon which is connected to the carriage so as to move the carriage upon rotation of the screw.

It is a still further object of the invention to provide a piler mechanism having an overhead conveyor and means for mounting in adjustable relation thereon an end stop device wherein the mounting means comprises an elongate housing associated with the conveyor and forming a track for a carriage on which the end stop is suspended, an adjusting screw journaled in opposite ends of the housing and carrying a traveling nut which is connected to the carriage so as to move the carriage upon rotation of the screw, and a device for supporting the adjusting screw at one or more points intermediate its ends which is automatically positioned in accordance with the position of the carriage so as to prevent sag in the center portion of the screw.

These and other objects and advantages of the invention will be apparent from a consideration of the apparatus which is shown by way of illustration in the accompanying drawings wherein:

FIGURE 1 is a plan view of a sheet piler embodying therein the principal features of the invention, with portions broken away and other portions omitted;

FIGURE 2 is a side elevation of the sheet piler;

FIGURE 3 is an end elevation at the delivery end of the machine, to an enlarged scale;

FIGURE 4 is a cross section taken on the line 4—4 65 of FIGURE 1, to an enlarged scale;

FIGURE 5 is a longitudinal section taken generally on the line 5—5 of FIGURE 4, to an enlarged scale and with portions broken away;

FIGURE 6 is a partial cross section taken on the line 6—6 of FIGURE 5, to a reduced scale;

FIGURE 7 is a partial cross section taken on the line 7—7 of FIGURE 5;

FIGURE 8 is a fragmentary view taken on the line 8—8 of FIGURE 7; .

FIGURE 9 is a cross section taken on the line 9—9 of FIGURE 2, to an enlarged scale;

FIGURE 10 is a partial longitudinal section taken on the line 10—10 of FIGURE 1, to an enlarged scale and with portions broken away;

FIGURE 11 is a cross section taken on the line 11—11 of FIGURE 10, to an enlarged scale;

FIGURE 12 is a horizontal section taken on the line 12—12 of FIGURE 10, to an enlarged scale; 10

FIGURE 13 is a longitudinal section taken on the line 13—13 of FIGURE 12 to a still larger scale; and

FIGURE 14 is a longitudinal vertical section taken on the line 14—14 of FIGURE 11 to an enlarged scale and with portions broken away.

The apparatus which is illustrated in the drawings and which has incorporated therein the principal features of the invention is designed to receive individual metal sheets 10 (FIGURE 2) from a processing line, or the like, and to deposit the sheets one by one on a stack or pile 11 for removal from the apparatus.

The apparatus comprises an upright supporting frame structure 12 (FIGURES 1 to 4) on which there is mounted a horizontally disposed vertically reciprocable bed structure 13 for receiving a stack or pile of metal sheets 10 and an overhead magnetic conveyor 14, the latter being operable to deposit successive sheets 10 in stacked relation on the bed structure 13.

The supporting frame structure 12 comprises longitudinally spaced end frames 15 and 16 which are connected at the bottom by parallel, relatively spaced, longitudinally extending side beams 17 and at the top by similar longitudinally extending side beams 18.

The sheets 10 are delivered to the bottom run of the conveyor 14 of the apparatus by a feed conveyor 20 which is supported on a suitable bracket member 21 on the end frame 15. The conveyor 14 comprises a series of transversely spaced conveyor rail units 22 which rail units are the magnetic type, for example, as disclosed in my Patent No. 2,642,174, dated June 16, 1953. The rail units 22 are supported at the receiving end of the apparatus on a cross beam 23 extending between vertical support brackets 24 on the upper portion of the end frame 15. At the other end of the apparatus the rail units 22 are supported on a cross beam 25 which extends between the upright brackets 26. The belt driving drums or sheaves of the rail units 22 are mounted on a cross shaft 27 which is journaled at its ends in the upstanding side brackets 26 and carries a sheave 28 connected by a drive belt 30 with an output sheave 31 on a motor reduction unit 32, the latter being supported on a top plate 33 on the end frame 16, which top plate 33 extends between spaced upright side plates 34.

The stack or pile supporting platform or table 13 (FIGURES 2 to 4) comprises a series of rollers 35 supported on suitable shafts which are journaled at their ends in laterally spaced side frame members 36 and a center frame member 37. The table 13 may be provided with raising and lowering mechanism of either a mechanical or hydraulic type. A suitable arrangement for raising and lowering the table 13 is disclosed in my pending application Serial No. 692,319, filed October 25, 1957, wherein the table is connected at its four corners to nut carrying bracket members which are mounted for vertical travel on upright driven screws. In the present apparatus the table elevating screws would be housed in the corner posts 38 and 40 on the end frames 15 and 16.

The apparatus is provided with a pair of longitudinally extending parallel side guide devices 41 and 42 (FIGURES 1 to 9) which are identical except for being rights and lefts and which are mounted on the pilier frame structure 12 in an identical manner. Only the side guide 41 and its mounting structure will be described, it being un-

derstood that the other side guide 42 is constructed and mounted on the machine in an identical manner.

The side guide 41 (FIGURES 5 to 7) is made up of a vertically disposed back plate 43 and an outwardly extending horizontally disposed reinforcing web plate 44 which is secured at its inner edge to the back plate 43 intermediate its top and bottom edges. A channel member 45 is secured with its open side against the lower portion of the inner face of the back plate 43, to form therewith a rectangular housing, with the web portion or inwardly directed face of the channel member 45 being in a vertical plane and forming a vertical guide face for engagement by the side edge of a sheet 10 when it is dropped by the conveyor 14. The channel member 45 is of a lesser height than the back plate 43 and the top portion of the guide is filled in by a curved plate section 46 forming a rounded top edge for guiding the edge of the sheet 10 towards the center of the apparatus.

The side guide 41 is supported at its opposite ends 20 on carriage structures 47 and 48 (FIGURES 5 and 7) which are mounted in sliding relation on track forming cross members 49 and 50, respectively. The carriage structure 47 at the entrance end of the apparatus is slidably supported on a vertically disposed cross beam or 25 track forming rail 49 which forms one vertical side of the cross frame housing structure 51 which extends across the end of the apparatus on the end frame 15. The carriage 47 (FIGURES 5 and 6) comprises a vertical plate 52 and a horizontally extending plate 53 secured intermediate the top and bottom edges of the outer face of the vertical plate 52 and extending towards the entrance end 30 of the apparatus. The horizontal plate 53 carries on its bottom face a downwardly opening channel-shaped slide member 54 which straddles the top of the track forming cross rail 49. A bearing angle member 55 is secured at the bottom edge of the vertical plate 52 on the lower end of a vertical filler plate 56 and is positioned with its vertical leg riding against the inner face of the cross rail 49 and with its horizontal leg riding on the top of a horizontally disposed bottom plate 57 which is secured to the bottom edge of the cross rail 49. The bottom plate 57 extends outwardly and has at its outer edge an upstanding plate 58 arranged parallel with the cross rail 49 and spaced therefrom by an intermediate horizontal plate 58' to form 40 with the cross rail 49 and the bottom plate 57 an upwardly 45 opening housing in which an adjusting screw 60 is mounted.

The adjusting screw 60 (FIGURES 5 and 6) is suitably journaled in end plates 61 on the housing structure and is provided with right and left hand threads extending from 50 the center thereof towards the ends. The screw 60 carries a nut 62 which is confined between the downwardly projecting axially spaced legs 63 of an inverted U-shaped saddle 64, the latter being secured to the bottom face of the horizontal plate 53 adjacent the slide 54 and extending 55 into the housing 51, with the legs 63 cut out at their bottom edges to accommodate the screw 60. The adjusting screw 60 carries at one end a pulley 65 (FIGURE 1) which is connected by a drive belt 66 with the output 60 pulley of a motor reduction unit 67 supported on a cross frame plate member on the end frame 15.

The vertical plate 52 of the carriage 47 has a relatively narrow horizontal flange forming plate 68 (FIGURE 5) at its upper end on which the end of the side guide member 41 is adapted to rest. The side guide 41 is provided with a vertical end plate 69 and a horizontal base plate 70 which is bolted or otherwise secured on the plate 68 of the carriage. An equalizing shaft 71 is mounted in the guide 41 which is journaled in the end plate 69 and carries on its end a pinion 72 in operative engagement with a rack 73 mounted on the upper flange of an outwardly facing cross channel 74, which channel 74 extends across the end frame 15 above the housing 51.

The side guide 41 is supported at the other end of the apparatus on the carriage 48 (FIGURES 5 to 8) which 75 comprises a downwardly opening channel-shaped slide or

carriage member 75 having mounted therein a similarly shaped bearing slide 76 which straddles the track forming cross rail 50. The slide member 75 also carries a horizontally disposed keeper member 77 on the lower edge of its outer leg which has its inner edge extending into a guide slot 78 in the outer vertical face of the cross rail 50. The slide member 75 has a pair of laterally spaced vertically extending plates 79 and 79' secured to its inner leg which are adapted to provide a slot formation 80. An angular end bracket 81 is secured on the end of the side guide 41 which has a horizontal leg 82 which is slotted at 83 to receive an upstanding pin 84 on the slide member 75, the pin 84 being provided with a washer 85 and a cotter pin 86, the latter being readily shearable upon substantial upward pressure being applied to the side guide structure 41. The top face of the slide member 75 is recessed at 87 to receive the top horizontal leg 82 of the bracket 81. The bracket 81 has a vertical leg 88 secured to the end plate 89 on the end of the side guide 41 which is provided with a vertically disposed outwardly extending plate member 90 which is adapted to be received in the slot 80 formed by the inwardly extending plates 79 and 79' on the carriage 48. The shaft 71 is journaled at this end of the guide 41 in the end plate 89 and carries a pinion 91 on its end which is in operative engagement with a rack 92 supported on the horizontal leg of an angle bracket 93 which is secured on the bottom of the cross rail 50.

The movement equalizing shaft 71 in the side guide 41 is supported intermediate the ends of the guide 41 on a center bearing (FIGURE 9) which comprises a vertically extending post 94 having its upper end curved to fit the periphery of the shaft 71 and mounted at its lower end in a sleeve 96 which is secured in the bottom wall of the guide structure and which is provided with a bottom plug 97. The post 94 is keyed at 98 to the sleeve 96 and suitable oil passageways are provided with an oil plug 99 in the sleeve plug 97 to facilitate lubricating the mechanism. The support prevents sagging of the relatively long shaft 71.

The side guide 42 on the opposite side of the apparatus is arranged to cooperate with the side guide 41 and is carried on the cross rails or tracks 49 and 50 on carriages identical with the carriages 47 and 48 so that rotation of the screw 60 moves the side guides 41 and 42 toward and from the center of the machine. The side guides are held in parallel relation during their movement by the movement equalizing shafts and the rack and pinion connections at the ends of these shafts. The racks extend at their inner ends to the vertically disposed back stop 100 (FIGURES 2 and 4) so that the inner limit of movement of the side guides is approximately the side edges of the back stop plate 100.

With the arrangement described, the side guides 41 and 42 are carried on the track forming cross rails 49 and 50 so that any substantial upward pressure will merely lift the side guides, shearing the cotter pin 86 at one end and raising the saddle 64 at the other end. This avoids damages to the side guides and their operating mechanism in the event the operator carelessly raises the table 13 to too high a point where it strikes the side guides.

An end stop mechanism 101 (FIGURES 1, 2 and 10 to 13) is provided which is mounted on the center unit 22 of the conveyor 14. The end stop mechanism 101 comprises an elongate track forming housing 102 mounted in longitudinally extending relation on the center conveyor unit and a movable end stop carriage structure 103 which is slidably mounted on the housing 102. The end stop carriage structure 103 comprises a horizontally disposed support plate 104 which carries on its upper face a pair of upstanding parallel bearing brackets 105 and 105' between the upper ends of which there is pivotally mounted at 106 an air cylinder 107 having its piston 108 extending downwardly and connected at 109 to the free

end of an operating arm 110 which is mounted in the center of a cross shaft 111, the latter having its ends journaled in upstanding bearing brackets 112 and 112' on the upper face of the support plate 104. A pair of relatively long, laterally spaced link members 113 and 113' are mounted near their upper ends on the cross shaft 111 and are pivotally connected at their upper ends by horizontal linkages 114 and 114' with the upper ends of a pair of parallel links 115 and 115', the latter in turn being secured on a cross shaft 116 which is journaled at its ends in upstanding bearing brackets 117 and 117' on the upper face of the support plate 104 at the opposite end thereof. The depending legs of the two pairs of links 113, 113' and 115, 115' are pivotally connected to the horizontal arms 118, 118' of a pair of L-shaped bracket members 120, 120'. The bracket members 120, 120' have on their vertical arms 121, 121' inwardly directed flanges 122 and 122' which are connected by a web plate 123 having at its center in vertically disposed alignment a pair of bearing ears 124 and 124'.

The bearing ears 124 and 124' fit between a pair of aligned vertically spaced mounting ears 125 and 125' which extend from the center of the back face of the supporting or backing plate structure 126 for the bumper pad 127. A hinge pin 128 extends through the vertically aligned apertures in the bearing ears 124 and 124' and is secured in the mounting ears 125 and 125' on the backing plate 126 to pivotally connect the plate 126 to the web plate 123. A bracket member 130 extends from the upper ear 125 which is connected to the center portion of a tension spring 131, the latter having its ends secured to the bracket members 120 and 120', so that the bumper support plate 126 is pivotally mounted for swinging movement on a vertical axis on the web plate 123. The horizontal movement of the bumper plate is cushioned by the air cylinder 107 through the linkage 110, 113, 115, 118 and 120.

The carriage 103 of the end stop mechanism comprises a downwardly facing channel-shaped slide member 132 (FIGURES 11 and 14) which is secured on the bottom face of the horizontal support plate 104 and which rests on the two laterally spaced track forming plates 133 and 133' on the top of the housing 102. The track plates 133, 133' have their longitudinal oppositely disposed or outside edges extending beyond the vertical faces of the two oppositely disposed channel members 134 and 134' which form the vertical sides of the housing 102. The edge flanges of the slide plate 132 are provided with keeper plates 135 and 135' for retaining the slide 132 on the track plates 133 and 133'.

The slide plate 132 has attached along the center of its bottom face a depending bracket or cage structure 136 which has a neck portion 137 extending downwardly between the track plates 133 and 133' and a cage forming portion comprising top and bottom plates 138 and 138' with axially spaced end plates 140 and 140' which are bored to accommodate the adjusting shaft or screw 142 which is supported in the housing 102. The screw 142 carries a nut 143 which fits between the end plates 140 and 140' of the cage 136 so that rotation of the screw imparts axial movement to the nut 143 and the cage 136 and causes the carriage 103 to travel on the housing 102.

The screw 142 is journaled at its opposite ends in the ends of the elongate housing 102 and at one end thereof carries a sprocket 144 (FIGURE 2) which is connected by the drive chain 145 with the output sprocket 146 on a drive motor unit 147 mounted by a suitable bracket plate on the top of the end of the housing 102.

The housing 102 and the adjusting screw 142 are provided with a slidably center support or brace mechanism (FIGURE 14) which comprises the axially spaced end block members 148 and 148' and a pair of connecting rods 149 and 149', the latter being secured at opposite ends to the block members 148 and 148'. The block

members 148 and 148' which are spaced apart a distance approximately half the length of the housing 102 are formed with axial bores which accommodate the screw 142 and are constructed so that the members 148 and 148' will slide freely within the housing 102. The carriage 103 is mounted initially on the housing 102 with the depending cage structure 136 and the associated nut 143 in the space between the two block members 148 and 148' of the sliding brace mechanism. With this arrangement when the carriage 103 is moved in one direction along the housing 102 by operation of the screw 142 the cage 136 will engage the block member 148 and carry the same towards one end of the housing 102. When the carriage 103 moves in the opposite direction by rotation of the screw 142, the cage 136 will engage with the opposite block member 148' and carry the center brace members towards the other end of the housing 102 so that regardless of the position of the carriage 103 the screw 142 is supported intermediate its ends with the maximum unsupported distance being the distance between the two members 148 and 148'. This arrangement prevents sag in the adjusting screw 142.

With the end stop mechanism 101 being mounted on the carriage 103 which is slidably supported on the longitudinally extending housing 102 and connected to the traveling nut 143 on the adjusting screw or shaft 142 the position of the end stop 127 may be readily and quickly adjusted at any time without stopping the piling conveyor.

While particular materials and specific details of construction have been referred to in describing the form of the apparatus illustrated, it will be understood that other materials and equivalent structural details may be resorted to within the spirit of the invention.

I claim:

1. In a sheet handling apparatus, longitudinally spaced upright end supporting frames, an overhead magnetic conveyor arranged above said end frames for advancing successive metal sheets to a point for deposit on a pile between said end supporting frames, parallel side guide members carried at their ends on said end supporting frames, said side guide members having vertically disposed parallel sheet edge guiding faces, transversely extending, horizontally disposed racks arranged on each of said end frames, each of said side guide members having rotatably mounted thereon a longitudinally extending shaft which is provided at opposite ends with pinions positioned for operative engagement with said racks, traveling carriages connected to opposite ends of each of said side guides, cross members on each of said end frames forming guide rails supporting said carriages for transverse movement, an adjusting screw journaled in transversely extending relation on one of said end supporting frames, a drive means operatively connected to said adjusting screw for rotating the same, said adjusting screw having right and left hand threads on opposite ends thereof and a pair of traveling nuts thereon, said nuts being connected to the carriages which are at the ends of said side guide members adjacent said adjusting screw whereby the distance between said side guide members is adjusted by rotation of said adjusting screw.

2. A sheet piler comprising an upright supporting frame, an overhead conveyor and side guiding devices adjustably mounted on said frame beneath said conveyor, said side guiding devices each comprising an elongate frame having a vertical face extending longitudinally of the piler, transversely extending bars on said frame which form guide rails for supporting opposite ends of said side guiding devices, one of said guide rails having a pair of carriages slidably mounted thereon, each of said carriages having an upwardly opening socket forming recess, each of said side guiding devices having at one end a member which is adapted to seat in the socket forming recess of one of said carriages and a safety connecting means between said end member and the carriage which normally holds the member in the socket forming recess so that the side guiding device and the carriage move transversely of

the machine as a unit, and said connecting means including a member which is readily breakable upon substantial upward force being applied to the side guiding device thereby to permit the side guiding device to be raised and freed from the carriage without damage to the side guiding device or the carriage.

3. A sheet piler comprising an upright supporting frame, an overhead conveyor and sheet side edge guiding devices adjustably mounted on said frame beneath said conveyor, said sheet guiding devices each comprising an elongate frame having a vertical face extending longitudinally of the piler, longitudinally spaced cross members on said frame which form guide supports for opposite ends of said sheet guiding devices, one of said cross members having carriages slidably mounted thereon, each of said carriages having an upwardly opening pocket forming recess, each of said sheet guiding devices having a member on one end which is adapted to seat in the pocket forming recess of one of said carriages and a connecting means between the end member of the sheet guiding device and the carriage which normally holds the member in the pocket forming recess so that the sheet guiding device and the carriage move transversely of the machine as a unit, and said connecting means being separable upon upward force being applied to the sheet guiding device to permit the sheet guiding device to be lifted in a vertical direction and freed from the carriage without damage.

4. A sheet piler comprising an upright supporting frame, an overhead conveyor and sheet side edge guiding devices mounted on said frame beneath said conveyor for adjustment toward and from each other, said side guiding devices each comprising an elongate frame having a vertical face extending longitudinally of the piler, longitudinally spaced cross bars on said frame for supporting opposite ends of said side guiding devices, one of said cross bars having a pair of carriages slidably mounted thereon, each of said carriages having an upwardly opening recess and an upwardly facing supporting surface with an upstanding pin thereon, each of said side guiding devices having a member on the end which has a portion adapted to seat in the recess of one of said carriages and a portion providing a downwardly facing surface for engagement with said upwardly facing surface, which portion is apertured to receive said pin whereby said side guiding device and said carriage are held against relative movement in the direction transversely of the piler while the side guiding device may move relative to said carriage in a vertical direction upon substantial upward force being applied to the said side guiding device.

5. A sheet piler comprising an upright supporting frame, an overhead conveyor and sheet side edge guiding devices adjustably mounted on said frame beneath said conveyor, said side guiding devices each comprising an elongate frame having a vertical face extending longitudinally of the piler, cross bars on said frame forming support rails for opposite ends of said side guiding devices, one of said cross bars having a pair of carriages mounted in fully slidable relation thereon, means holding said carriages against vertical movement on said cross bars, each of said side guiding devices having at one end a member which is seated in separably mounted relation on one of said carriages and a connecting means between the end member on the side guiding device and the carriage which normally holds the end member and the carriage in connected relation and which is readily separable upon substantial upward force being applied to the side guiding device to permit the side guiding device to be lifted and separated from the carriage without damage to either the side guiding device or the carriage.

6. A sheet piler comprising an upright supporting frame, an overhead conveyor and side guide devices adjustably mounted on said frame beneath said conveyor, said side guide devices each comprising an elongate frame having a vertical face extending longitudinally of the piler, transversely extending bars on said frame which form guide rails for supporting opposite ends of said side guide devices,

each of said transverse bars having a pair of carriages slidably supported thereon, each of the carriages on one of said transverse bars having an upwardly opening recess, each of said side guide devices having at one end a member which is adapted to seat in the recess of one of said carriages and a connecting means between said end member and the carriage which normally holds the member in the recess and which is readily separable upon substantial upward force being applied to the side guide device to permit separation of the member from the carriage in a vertical direction, said side guide devices having members on the other ends thereof which are secured to the carriages on the other one of said transverse bars, said last mentioned carriages being adapted to be lifted from their supporting bar upon upward force being applied to the side guide devices, said side guide devices each having a movement equalizing shaft journaled therein which carries pinions adjacent the ends thereof and fixed transverse racks on said supporting frame for engagement with said pinions.

7. In a sheet handling apparatus having an upright supporting frame and an overhead endless belt type magnetic conveyor having a bottom run adapted to advance successive metal sheets to a point for deposit on a pile, an end stop mechanism comprising an elongate housing extending lengthwise of the apparatus and supported above the bottom run of said endless conveyor, a carriage mounted for adjustment along said conveyor, a pair of vertically extending, longitudinally spaced parallel links pivoted intermediate their ends on said carriage, said links being pivotally connected at their lower ends below said conveyor to one leg of an L-shaped bracket, a bumper device mounted on the other leg of said L-shaped bracket with a vertically arranged face which is adapted to be engaged by the leading end of each successive sheet as it is released by the conveyor, means connected to said parallel links for resisting pivotal movement of said parallel links thereby to cushion the impact of the sheets against the bumper device, said housing having an elongate threaded adjusting shaft mounted therein, said carriage having a saddle thereon which straddles said shaft and a traveling nut carried on said shaft and engaging with said saddle to move the saddle along the shaft when the shaft is rotated, and means to rotate the shaft in either direction so as to adjust the position of the bumper device.

8. In a sheet handling apparatus as recited in claim 7, and a shaft bracing device mounted in said housing which comprises an elongate frame, said frame having at its opposite ends slide members which are movable lengthwise in the housing and which are apertured to receive the shaft, said bracing device being approximately half the length of said adjusting shaft and said end members being engageable by the saddle on the carriage when the carriage is moved to predetermined positions along the shaft so that said shaft is supported by said end members at points intermediate the ends thereof so as to prevent sagging thereof.

9. In a sheet handling apparatus having an upright supporting frame and an overhead endless belt type conveyor having a lower run for advancing successive metal sheets to a point for deposit on a pile, an end stop mechanism comprising an elongate housing extending lengthwise of the apparatus and supported above the lower run of said endless conveyor, a carriage mounted in sliding relation on said housing for adjustment along said conveyor, a pair of vertically extending, longitudinally spaced parallel links pivoted intermediate their ends on said carriage, said links being pivotally connected below said conveyor to a horizontally disposed leg of an L-shaped bracket, a bumper device mounted on the vertically disposed leg of said L-shaped bracket with a vertically arranged face positioned to be engaged by the leading ends of successive sheets as they are released by the conveyor, cushioning means for resisting pivotal movement of said parallel links so as to absorb the impact force of the sheets against the bumper device, said

housing having a threaded adjusting shaft mounted therein and a longitudinally extending slot in the upper side thereof, said carriage having a saddle depending therefrom which extends through the slot in the housing and which straddles the threaded shaft and a traveling nut carried on said shaft and connected to said saddle to move the saddle along the shaft when the shaft is rotated, and means to rotate the shaft in either direction so as to adjust the position of the bumper device.

10. In a sheet handling apparatus as recited in claim 9 and a shaft bracing device mounted in said housing which comprises an elongate frame, said frame being of lesser length than said housing and having at its opposite ends slide members which are movable lengthwise in the housing, said slide members being apertured to receive the shaft, and a projecting member on said carriage engaging said end members whereby when the carriage is moved to predetermined position along the shaft said shaft is supported by said end members at points intermediate the ends thereof so as to prevent sagging.

11. In a sheet handling apparatus, an upright supporting frame, an overhead magnetic conveyor arranged on said supporting frame for advancing successive metal sheets to a point for deposit on a pile receiving means beneath the same, side guide members carried in parallel relation on said supporting frame, said side guide members having oppositely disposed vertically extending sheet edge guiding faces, transversely extending, horizontally disposed, longitudinally spaced racks arranged on said frame, each of said side guide members having rotatably mounted thereon a longitudinally extending shaft which is provided at opposite ends with pinions positioned for operative engagement with said racks, a single adjusting screw journaled in transversely extending relation at one end of said supporting frame, a drive means operatively connected to said screw, said screw having right and left hand threads on opposite ends thereof, a pair of traveling nuts on said screw, said side guide members each having a bracket at the end adjacent said adjusting screw with a portion of said bracket seated on one of said traveling nuts so as to move with said nut when said screw is rotated, said bracket portion being free to move vertically relative to said nut whereby the distance between said side guide members is adjusted by rotation of said screw and said guide members will move upwardly of said nuts without damage if a substantial upward force is applied to the lower face thereof by upward movement of said pile receiving means so as to engage said guide members.

12. A sheet piler comprising an upright supporting frame, an overhead conveyor, a vertically movable pile receiving platform beneath said conveyor, and sheet side edge guides adjustably mounted on said frame beneath said conveyor, said side guides each comprising an elongate frame having a vertical face extending longitudinally of the piler, cross bars on said frame forming guide rails for supporting opposite ends of said side guides, each of said cross bars having a pair of carriages slidably mounted thereon, the carriages on one of said cross bars each having an upwardly opening recess, each of said side guides having at one end a bracket member which is disposed in the recess of one of said last mentioned carriages so that the side guide moves with the carriage when the carriage is moved transversely and the bracket is free to move vertically so as to separate from the carriage, each of said side guides having a bracket member on its other end which is secured to a carriage on the other one of said cross bars, the carriages on said last mentioned cross bars being mounted on said cross bars so that they are free to move in an upward direction and separate from said cross bars upon substantial upward force being applied to the side guide by improper raising of said pile receiving platform so as to strike said side guides, an adjusting screw mounted adjacent said last mentioned cross bar, a pair of traveling nuts on said ad-

justing screw and means connecting said nuts and the carriages on said last mentioned cross bar which permit upward movement of said carriages away from said nuts when said upward force is applied.

13. A sheet piler comprising an upright support frame, an overhead longitudinally extending belt type magnetic conveyor, an end stop mechanism, and an adjustable mounting for said end stop mechanism, said mounting comprising an elongate overhead housing having means forming a longitudinally extending track formation above the lower sheet engaging run of said conveyor, a carriage mounted on said housing for movement along said track formation, a power driven adjusting screw mounted in said housing in parallel relation adjacent said track formation, a bracing means positioned intermediate the ends of said screw for supporting said screw against downward bowing, a traveling nut on said screw, means restraining the nut against rotation relative to said track formation, said nut being connected to said carriage so as to move said carriage longitudinally of said conveyor upon rotation of said screw, a bumper device having a vertical sheet edge engaging face, a bracket pivotally mounted on said carriage and depending therefrom, said bracket being connected at its lower end to said bumper device so as to suspend the bumper device below the lower run of said conveyor and means on said carriage connected by a linkage to said bracket for cushioning the retractive movement of said bumper device when a sheet strikes said vertical face.

14. A sheet piler comprising an upright support having end cross frames, an overhead conveyor mounted on said end cross frames, an end stop mechanism, and an adjustable mounting for said end stop mechanism, said mounting comprising an elongate overhead housing having a slotted top portion forming a track, a carriage mounted for movement along the track forming top of said housing, an adjusting screw rotatably mounted in longitudinally extending relation in said housing, a traveling nut on said screw, means restraining the nut against rotation in said housing, said nut having a portion extending through the slot in the top of said housing and being connected to said carriage so as to move said carriage upon rotation of said screw, a bracket depending from said carriage and straddling said housing, a bumper device pivotally connected to said bracket, said bumper device having a vertical sheet edge engaging face extending below said overhead conveyor and means mounted on said carriage and connected to said bracket for cushioning the retractive movement of said bumper device when a sheet strikes said vertical face.

15. A sheet piler comprising an upright support having longitudinally spaced end frames and laterally spaced side guides, an overhead longitudinally extending rail-like belt type conveyor intermediate said side guides, an end stop mechanism, and an adjustable mounting for said end stop mechanism, said end stop mounting comprising an elongate longitudinally extending track formation supported at opposite ends on said end frames above said conveyor, a carriage mounted for sliding movement along said track formation, a power driven adjusting screw mounted in parallel relation adjacent said track formation, bracing means intermediate the ends of said screw to prevent downward bowing of said screw, a traveling nut on said screw, means restraining the nut against rotation relative to said track formation, said nut having a connection with said carriage so as to move said carriage along said track upon rotation of said screw, a swingable bracket depending from said carriage and straddling said track formation and said conveyor, a bumper device having a vertical sheet edge engaging face connected to said bracket, and fluid operated means for cushioning the retractive movement of said bumper device when a sheet strikes said vertical face.

16. A sheet piler comprising an upright support hav-

ing longitudinally spaced end frames and laterally spaced side guides, an overhead longitudinally extending rail-like belt type conveyor intermediate said side guides, an end stop mechanism, and an adjustable mounting for said end stop mechanism, said end stop mounting comprising an elongate, longitudinally extending track formation supported at opposite ends on said end frames above said conveyor, a carriage mounted for sliding movement along said track formation, a power driven adjusting screw mounted in parallel relation adjacent said track formation, bracing means intermediate the ends of said screw to prevent downward bowing of said screw, a traveling nut on said screw and having a connection with said carriage so as to move said carriage upon rotation of said screw, a swingable bracket depending from said carriage and straddling said conveyor, a bumper device having a vertical sheet edge engaging face connected to said bracket, and a fluid operated means for cushioning the retractive movement of said bumper device when a sheet strikes said vertical face, said bracing means comprising an elongate frame, said frame having at its opposite ends slide members which are connected in sliding relation with said track formation and which are apertured to receive said adjusting screw, said bracing means extending a substantial portion of the length of said screw and said end members being engageable by said end stop carriage when the carriage is moved to predetermined positions along the screw so that said bracing means is positioned with the slide members at points intermediate the ends of said screw whereby to prevent sagging thereof.

17. A sheet piler comprising an upright support frame, an overhead belt type magnetic conveyor, an end stop mechanism, and an adjustable mounting for said end stop mechanism, said mounting comprising an elongate, longitudinally extending track formation mounted adjacent said conveyor, a carriage mounted for movement along said track formation, a power driven adjusting screw mounted in parallel relation adjacent said track formation, a traveling nut on said screw, said nut being connected to said carriage so as to move said carriage upon rotation of said screw, a bumper device having a vertical sheet edge engaging face, a bracket forming frame swingably mounted in depending relation from said carriage, means mounting said bumper device on said bracket with the sheet edge engaging face extending in the path of the sheets below said overhead conveyor, means mounted on said carriage and connected to said bracket forming frame for cushioning the retractive movement of said bumper device when a sheet strikes said vertical face, and a bracing device for said adjusting screw which comprises an elongate frame, said frame having slide members at its opposite ends which are apertured to slidably receive the screw, said bracing device being approximately half the length of said screw and said end members being freely slidable along said track formation and being engageable by the carriage when the carriage is moved to predetermined positions along the screw so that said screw is supported in said end members at points intermediate the ends of the screw so as to prevent sagging.

18. A sheet piler comprising an upright support frame, an overhead belt type magnetic conveyor, an end stop mechanism, and an adjustable mounting for said end stop mechanism, said mounting comprising an elongate, longitudinally extending track formation mounted adjacent said conveyor, a carriage mounted for movement along said track formation, a power driven adjusting screw mounted in parallel relation adjacent said track formation, a traveling nut on said screw, said nut being connected to said carriage so as to move said carriage upon rotation of said screw, a bumper device having a vertical sheet edge engaging face, a bracket forming frame swingably mounted in depending relation from said carriage, means mounting said bumper device on said bracket with the sheet edge engaging face extending in the path of the sheets

75

below said overhead conveyor, means mounted on said carriage and connected to said bracket forming frame for cushioning the retractive movement of said bumper device when a sheet strikes said vertical face, said means mounting said bumper device on said bracket comprising a vertically disposed pivot connecting the bumper device with the bracket for relative swinging movement, and spring means for normally holding the bumper device with its sheet engaging face in a vertical plane which is substantially normal to the path of advance of the sheets.

UNITED STATES PATENT OFFICE
CERTIFICATE OF CORRECTION

Patent No. 3,061,305

October 30, 1962

Dario Buccicone

It is hereby certified that error appears in the above numbered patent requiring correction and that the said Letters Patent should read as corrected below.

Column 5, line 59, for "damages" read -- damage --; column 8, line 21, for "carirage" read -- carriage --; line 56, for "fully" read -- freely --.

Signed and sealed this 2nd day of April 1963.
